PRINTING-TELEGRAPH SYSTEM.

Application filed March 21, 1928. Serial No. 263,363.

This invention relates to printing telegraph systems of the class in which the operation of the distant receiver or receivers is controlled by current impulses sent over a transmission circuit under the control of a plurality of local controlling circuits at the transmitter. More particularly the invention relates to systems in which the local controlling circuits are themselves controlled by a perforated tape or strip of paper or other insulating material (the perforations being in transverse alignment) which passes between cooperating contacts in said controlling circuits. Since the tape is non-conducting no current flows from one contact to another except when a perforation is in registry with the two. The latter can then close, permitting current to flow in the circuit with which the particular contacts are associated. More especially our present invention pertains to the aforesaid contact mechanism, and its chief object is to provide convenient, effective and reliable contact mechanism of the mercury type, that is, mechanism in which a body of mercury serves as a contact common to a plurality of insulated contacts, the mercury being adapted to pass through the perforations in the tape and thereby engage singly the operating contacts on the opposite side of the tape. A further object is to provide simple and durable mechanism for the purpose, positive in operation and capable of use for long periods without the necessity of frequent repair or critical adjustment. To these and other ends the invention comprises the novel features of construction and combinations of elements hereinafter described.

The invention can be embodied in a considerable variety of forms, and of these we have selected for description herein the one which, at the present time is believed to exhibit the invention in its most convenient and effective form. This embodiment is designed particularly for use in the printing telegraph system described in our copending application Serial No. 110,850, filed May 22, 1926, in which the receiver is of the so-called "ticker" type, printing on a paper tape under the control of current impulses of alternating polarity the number of which in each group or train is controlled at the transmitter by a sunflower comprising an annular series of

insulated contacts and a revolving wiper which passes over the contacts in succession and is synchronized with a pole-changing switch in such manner that as the wiper passes off one contact and onto the next the current in the transmission circuit is reversed in polarity. The system thus briefly outlined may also include the so-called "magnetic shift" mechanism described in our copending application Serial No. 144,230, filed October 26, 1926, and the preferred form of our present invention is adapted to the use of the mechanism mentioned, as will be explained more fully hereinafter.

Referring now to the accompanying drawings:

Fig. 1 is a wiring diagram showing the electrical connections of the contact devices and so much of the wiring of the transmission system as seems useful in understanding the function of the perforated tape in controlling the transmitter and the distant receiver.

Fig. 2 is a plan view of the preferred form of contact mechanism.

Fig. 3 is a cross section on the line 3-3 of Fig. 2, showing the two mercury contacts, the transversely aligned fixed contacts above the mercury contacts and in cooperative relation to the latter, and the standpipes for putting a head on the mercury to cause the same to rise through the perforations in the tape.

Fig. 4 is a section on the line 4-4 of Fig. 2.

Fig. 5 is a side view of the contact mechanism, showing the electromagnetic devices which pass the perforated tape step-by-step between the mercury contacts and the fixed contacts.

Referring first to Fig. 1, 10 represents a receiver or "ticker" which may be of the well known type described in the patent of George S. Hiltz, No. 1,085,124, issued January 27, 1914, having a printing or "press" magnet 11 in a local circuit, supplied with current from the local main 12, and the third wire or grounded return 13, under the control of a relay 14. The escapement magnets 15, 16 are in series with the transmission line 17, as is also the "shift" magnet 18 which determines which of the two receiver type wheels (not shown) will make the imprint, as explained in our copending application Serial

No. 144,230, above referred to. The transmitter has a pole-changing switch comprising a pair of slip rings 19, 20 and brushes 21, 22, 23 on a shaft 24 driven by a constantly running motor, not shown, through a slipping clutch, not shown, which permits the shaft to be arrested without stopping the motor. Slip ring 20 has an insulating segments 20^a which, as the shaft revolves, 5 lifts brushes 22, 23 out of contact alternately. In the position shown, current flows from grounded brush 21 through magnet 25 of the pole-changing relay 26 to the current-supply main 27. The armature of the relay, represented by contact 28, is thus attracted by magnet 25 and engages contact 29, and positive current then flows from main 27 through wire 30, contacts 29, 28, armature 31 of the "repeat" magnet 32, wire 33, relay 108^a 10 (which controls the feed of the perforated tape through the transmission-controlling contact mechanism), resistance 35 and line wire 17 to the ticker press relay 14. When the rotation of shaft 24 carries insulating segment 20^a into cooperation with brush 23, brush 22 is then in engagement with ring 20 and current flows through magnet 36 of the pole-changing relay 26. Armature 28 is swung over to contact 37, whereupon negative current flows from main 38 through wire 39, contacts 37 and 28, and thence through the path traced above, to the receiver. In this way current impulses of rapidly alternating polarity are sent over the transmission line 15 as long as shaft 20 revolves. These impulses through the escapement magnets 15, 16 control in the usual way the rotation of the receiver type wheels (not shown) to bring the desired character to the printing position, 20 whereupon the shaft 24 is arrested. The impulse last sent (of whatever polarity it may be) is thus prolonged, thereby energizing the slow-acting relay 14 which then draws its armature over and closes the local circuit 25 of the press magnet 11. The latter then actuates the receiver platen, not shown. As long as the shift relay magnet 40 is deenergized resistance 35 remains in the transmission circuit; the current through shift magnet 18 30 is therefore too weak to energize the latter magnet, and hence all the imprints at the receiver are made from the same type wheel. When, however, the circuit of magnet 40 is closed (as hereinafter described) the armature 41 is raised, thereby laying a shunt or short circuit across the resistance, thus strengthening the line current to a value sufficient to energize the shift magnet which then causes the next imprint to be made from 35 the other type wheel.

Still referring to Fig. 1, the shaft 24 is arrested at the proper instant (when a sufficient number of current impulses have been sent to bring the desired character on the receiver type wheel to the printing position)

by an electromagnetic clutch or brake 42, which may be of a well known type, connected to ground and to the armature 42^a of a relay 43. The latter is connected to main 38 through lower mercury contact 44 and upper pin contacts 45, 46, 47, 48. Whenever current flows through contact 44 and any one of the four upper contacts the relay is energized and swings its armature over against contact 49, whereupon current flows in the clutch local circuit. Being thus energized, the clutch arrests the shaft 24 and the current then flowing continues to flow, with the results described above.

The transmitter is also provided with a "sunflower" 50, Fig. 1, comprising an annular series of twenty-eight insulated contacts, twenty-six of which are shown marked with the letters of the alphabet and two, diametrically opposite each other, are shown marked with dots, representing periods. The upper of these two is termed herein the "letters period" contact and the lower as the "figures period" contact. The sunflower contacts are connected to form seven sets of four each, one contact of each set being connected to one of every other group. Thus, upon tracing the connections it will be seen that contact "letters period" is connected to contacts H, "figures period" and T, these four constituting a "set". Similarly, contacts G, F, S, Z are connected together and so form another set. Each set is also connected to one of seven pin contacts 51, 52, 53, 54, 55, 56, 57, above the mercury contact 59, described hereinafter. Thus the set composed of contacts G, F, S, Z is connected to pin contact 57, and that composed of "letters period" H, "figures period" and T, is connected to pin contact 51. Inside of the outer series of contacts there are four insulated contacts 1, 2, 3, 4, each spanning seven contacts of the outer series and connected to the pin contacts 45, 46, 47, 48 respectively. The sunflower also has a wiper 58, fixed on a shaft 58^a which is connected with the motor-driven shaft 24 by reducing gearing (not shown) of such ratio that the wiper makes one revolution for each fourteen revolutions of the shaft 24. Since two current impulses are transmitted in each revolution of the latter shaft, it will be seen that twenty-eight impulses are sent in each revolution of the wiper 58. The latter has two electrically connected fingers bearing one on the outer contacts and the other on the inner, so that as the wiper revolves from the position shown in Fig. 1 it connects inner contact 1 to outer contacts A, B, C, D, E, G, in succession, then contact 2 to contacts H, I, K, L, M, N, F, and so on.

Suppose now that the letter A having been printed at the receiver it is desired to print D. Tracing the connections it will be seen that outer contact D is connected to pin contact 55 and inner contact 1 to pin contact 45.

Hence connection is made (as described hereinafter) between mercury contact 59 and pin 55 only, and between mercury contact 44 and pin 45 only. (If, as in the present embodiment, the letters are on the type wheel which prints only when strong current is transmitted, that is, when the resistance 35 is shunted out of circuit by energization of the relay 40, connection must also be made between contacts 44 and 66, in series with the relay and battery 40^a.) Now as the wiper moves counterclockwise the pole-changing switch or commutator sends alternating impulses to the receiver, whose type wheels follow in unison with the wiper until contact D is reached and type D at the receiver is at the printing position. Current now flows from main 38 through wire 60, relay magnet 43, contacts 44 and 45, wire 61 to inner sunflower contact 1, across the wiper to outer contact D, thence through wire 62, pin contact 55, mercury contact 59, wire 63, contact 68, unison key 64 and wire 65 to main 27. Relay 43, thus energized, closes the local circuit of the brake or clutch 42, and the latter arrests shafts 24 and 58^a. Letter D having been printed, suppose that the next letter is O. The circuit being broken at contacts 59—55 and 44—45 and made at 59—53 and 44—47 the clutch is deenergized, shaft 24 rotates and the wiper 58 moves over the sunflower contacts. Arriving at contact O the wiper finds the circuit of clutch relay 43 established through contacts 59—53 and 47—44, whereupon the clutch is energized as described and (contacts 44 and 66 being also closed) O is printed. In this way the receiver type wheels can be rotated step by step to bring to the printing position any one of the characters corresponding to the respective outer contacts on the sunflower.

As previously stated the receiver has two type wheels. These are mounted on the same shaft, with the characters on one in axial alignment with those on the other. Since (in the present instance) each wheel has twenty-eight character spaces each outer sunflower contact corresponds to two characters or character spaces, one on each wheel. In general one wheel has letters of the alphabet and the other carries numerals, fractions, and any special characters or symbols that may be desired. When (in the present system) it is desired to print from the second wheel, say a number or a fraction, or a special character, contacts 44 and 66 are not closed at the same time as the desired character-selecting contacts are closed, and hence resistance 35 is not shunted out and weak current is therefore sent over the line as explained above.

It will be readily seen that accuracy of printing depends upon keeping the receiver type wheels in step or in "unison" with the sunflower wiper. If the wheel gets out of unison, as sometimes happens, the operator

can bring it back into unison by depressing the unison key 64 to its neutral or mid-position. This opens the circuit through the clutch relays 43, so that the clutch cannot be energized even though the other contacts in the circuit be closed. Hence the sunflower wiper will revolve as long as the key is held in the position stated, and the receiver type wheels will also revolve until by means (not shown) provided for the purpose at the receiver they are brought to rest automatically with "letters period" at the printing position. The operator has before him a receiver (not shown herein) in circuit with the distant receiver, and when he observes the type wheels of his own receiver come to rest he depresses key 64 farther, bringing it into engagement with contact 67. On shaft 58^a is a cylinder 69 of insulating material carrying a conducting bar 70 axially aligned with the tips of the fingers on the wiper 58 and adapted to bridge the two brushes 71, 72 when the wiper is on the "letters period" contact. Brush 72 being connected with mercury contact 44 and brush 71 with the lower contact 67, it will be seen that with key 64 fully depressed current can flow through the clutch relay 43 when, and only when, the wiper is on the letters period contact (the upper of the two contacts marked with a dot). Hence when the revolving wiper comes to the contact mentioned current flows from main 38 through wire 60, contact 44, wire 73, brush 72, contact bar 70, brush 71, contact 67, key 64 and wire 65 to main 27. The clutch relay 43, being thus energized, closes the clutch local circuit and shafts 24 and 58^a are arrested with the wiper on the letters period contact. This method of coming to unison forms the subject of our copending application filed March 21, 1928, Serial No. 263,364.

Referring now to Fig. 3, the bodies of mercury 44, 59 are the similarly numbered contacts in Fig. 1, and the pins 45, 46, 47, 48, 66, 51, 52, 53, 54, 55, 56, 57 are the contacts having the same numbers in the figure last mentioned. The two mercury contacts are contained in narrow transversely elongated chambers in an insulating block 75 into which the horizontal metal tubes 76, 77 are snugly fitted. At their ends the tubes are bent to form standpipes 78, 79, in which the mercury extends, as shown. When the standpipes are upright the resulting head causes the mercury in the blocks 75 to rise into contact with the pins, but when the standpipes are turned down, as indicated in dotted lines, the mercury runs down into them and out of contact with the pins thereby preventing escape of the mercury when the tape or the insulating block 51^a is to be removed. The mercury bodies are connected in circuit by means of springs 80, 81, Fig. 2, having points 82, 83, Fig. 3, pressing firmly into recesses in the bosses 84, 85. The perforated tape 100, Fig. 4, passes

between the pins and the underlying bodies of mercury, and it will be seen that when a perforation comes under a pin the mercury rises through the hole into contact with the pin thus exposed. Hence the transverse spacing of the perforations in the tape determines the character printed at the receiver. Thus (referring to Figs. 3 and 1) with two perforations spaced to expose pins 52 and 48 to the underlying mercury, and a third perforation to expose pin 66 also, a figure will be printed. If the third perforation is omitted the receiver platen will be shifted to the other type wheel and a letter will be printed.

15 The tubular mercury containers 76, 77, Fig. 3, may be made in two parts, as shown, the standpipe portions 78, 79 being fitted into the ends of the horizontal portions. The former are slotted along one side, forming windows or sight-openings 78^a closed by inner glass tubes 79^a suitably sealed in place at top and bottom to prevent leakage of mercury. Screw-closures or caps 79^b are provided in the ends of the standpipes for easy supply 25 or withdrawal of mercury.

20 The contact pins 45, 46, 47, 48, 66, 51, 52, 53, 54, 55, 56, 57, Figs. 1, 3 and 4, are composed of heavy wires, for example copper or brass, and are mounted in a two-piece insulating body 51^a, and are bent to bring them up through suitable openings in the upper part of the supporting body into connection individually with a longitudinal row of terminal buttons 86 engaged by spring terminals 35 87 (shown best in Figs. 2 and 4) for connection with the corresponding sets of outer contacts and the four inner contacts on the sunflower. The block or body 51^a, carrying the contact pins, is held in place by screws 51^b, 40 Fig. 2, and when these are removed it may be slipped out from under the spring terminals for inspection or repair, etc. The terminals mentioned are mounted on an insulating block 89 supported by pillars 90 on block 75, which, 45 along with the tube-bearings 91, 92, is carried by the top plate or table 93 (see also Fig. 5) of the housing 94 in which the actuating solenoids of the punching mechanism are located.

50 As the tape passes between the upper and lower contacts to present successive groups of perforations thereto there is a tendency for the tape to carry minute globules of mercury away with it. In order to save any mercury thus carried away the block 75, Fig. 4, is provided with a recess or receiving chamber 95 over which the tape passes and into which the mercury drops and passes thence through an outlet or escape passage 96 to a funnel 97, open at the bottom. From the latter the mercury drops into a small receptacle not shown.

55 The control tape is drawn through the contact mechanism step by step by a sprocket wheel or roller 98, Figs. 2, 4, 5, cooperating with a central longitudinal row of holes in the tape. This roller, located at the outlet or dis-

charge end of the contact mechanism, is rotated by a pawl 101 engaging a ratchet 102. The pawl is pivoted on the rear end of an actuating lever 103 fulcrumed in a block 104 depending from the underside of the top plate 70 93. At the other end the lever is connected to a coil spring 105 by which it is urged clockwise to raise the pawl, and between the fulcrum and the pawl the lever is connected by a link 106 to the core 107 of an actuating solenoid 108. The pawl is held in engagement with the ratchet by a small coil spring 109, Fig. 5, between the pawl and its actuating lever. 75

80 The tape is held in engagement with the sprocket roller 98 by a cramp roller 98^a, and a holding pawl (not shown) may be employed in cooperation with the ratchet 102 if necessary or desirable, to prevent backward rotation of the ratchet and sprocket when the actuating pawl is advanced over the ratchet by the spring 105.

85 To enable the operator to advance the tape manually at will the journal 200 of the sprocket roller 98, Fig. 2, is provided with a pin 201 for engagement with a slotted collar on the adjacent end of a sliding shaft 202 mounted in a suitable bearing 203 and urged outwardly by a coil spring 204 between said bearing and the knurled button 205. The pin 90 201 can be engaged by pressing the shaft inwardly, whereupon the sprocket roller can be rotated by turning the button. 95

100 The relay 32, controlled by the normally closed contacts 32^a, controls the repeating mechanism described in our copending application Serial No. 110,850, mentioned hereinbefore, to which reference may be made for a detailed explanation. It is sufficient to say here that when a group of transmission controlling perforations in the tape is repeated, to cause the letter or character last printed at the ticker to be printed again, the repeat mechanism opens and closes the contacts 32^a, 105 with the result that (as explained in our application aforesaid) the ticker tape is advanced one step and the press magnet is energized without rotation of the ticker type wheel and of the wiper on the transmitter 110 sunflower. 115

120 The solenoid magnet 108, which draws the perforated tape step by step through the contact mechanism, as above described, is controlled by a relay 108^a, in the transmission circuit connecting the transmitter and the distant receiver or receivers, as indicated in Fig. 1. The relay 108^a is not energized by the rapidly alternating character-selecting impulses sufficiently to actuate its armature but when the final impulse is prolonged (by 125 arrest of the shaft 24 as explained above) to print the character at the receiver the relay is fully energized and closes the local circuit of feed magnet 108. It will therefore be seen that each time the receiver prints a char- 130

acter the feed solenoid is energized and the pawl 101 is drawn down, thereby feeding the tape forward one step and bringing the next group of control perforations to the contacts. 5 When the transmission circuit is broken (as a result of the movement of the tape) the pawl is raised by the spring 105 into position for the next feeding operation. Preferably the feed of the tape takes place just after the printing 10 and hence the relay 108^a is made slightly slower in action than the relay 14 which controls the press magnet 11.

Preferably the perforated tape 100 comes to the contact mechanism directly from the 15 mechanism which punches the perforations in the tape, as for example the mechanism illustrated in Fig. 4. This mechanism is described and claimed specifically in our co-pending application Serial No. 263,362, filed 20 March 21, 1928, and hence need not be described in detail herein. It will be sufficient here to explain that it comprises a transverse row of punches 110, cooperating with a die-plate 115 and actuated by levers 119 which are 25 themselves actuated by solenoids 123. The tape is drawn through the punching mechanism by a sprocket roller 124, rotated step-by-step in harmony with the punching devices by any convenient mechanism, not shown, as 30 for example the mechanism described in our aforesaid application Serial No. 263,362.

Since the tape is fed positively through the contact mechanism and is also fed positively through the punching mechanism, it will be 35 seen that to prevent tearing the tape the feed past the contacts should be no faster than the delivery from the punching devices. On the other hand, if the punching mechanism is operated under manual control of the operator he may not keep up with the contact feed at all times, and to prevent damage to the tape under such circumstances we control the contact feed in such way that the feed will cease if for any reason the tape is not 40 supplied to it fast enough. For this purpose the local circuit of the feed magnet 108 is provided with a pair of contacts 145, 146, Figs. 1 and 4. The latter contact, which is pivoted and normally held on the other by a spring, 45 not shown, has a finger 147 underlying the tape 100 between the sprocket roller 124 and the contact devices. So long as the operator keeps the punching mechanism working fast enough to maintain at least a small loop of 50 tape above the finger 147 the contact feed continues to operate, but should the punching operation be slowed up too long the tape, advanced at a faster rate by the contact feed, will engage the finger and by downward pressure thereon rock the contact 146 out of engagement with the contact 145, thereby breaking the circuit of feed magnet 108 before all 55 the slack between the two mechanisms is taken up. It is then necessary for the operator to speed up the punching operation,

thereby releasing the contact 146 and permitting it to close again on contact 145.

It is to be understood that the invention is not limited to the specific construction herein illustrated and described but can be embodied 70 in other forms without departure from its spirit.

We claim—

1. In a tape-controlled printing telegraph system, in combination, mechanism for advancing a perforated tape longitudinally, a body of insulating material adjacent to the path of the tape and having a transverse mercury reservoir adapted to be closed by the tape, an insulating body spaced from the first and having a transverse row of contacts for engagement with mercury protruding through perforations in the tape, and means operable to put a hydrostatic head on the mercury in said reservoir or to relieve such head, at will. 75

2. In a tape-controlled printing telegraph system, in combination, mechanism for advancing a perforated tape longitudinally, a body of insulating material adjacent to the path of the tape and having a transverse mercury reservoir adapted to be closed by the tape, an insulating body spaced from the first and having a transverse row of contacts for engagement with mercury protruding through 80 perforations in the tape, and means operable to put a hydrostatic head on the mercury in said reservoir or to relieve such head, at will, said means comprising a mercury container communicating with said reservoir and adapted to be raised and lowered relatively to the reservoir. 95

3. In a tape-controlled printing telegraph system, in combination, mechanism for advancing a perforated tape longitudinally, a body of insulating material adjacent to the path of the tape and having a transverse mercury reservoir adapted to be closed by the tape, an insulating body spaced from the first and having a transverse row of contacts for engagement with mercury protruding through 105 perforations in the tape, and a pivoted mercury container communicating with the mercury reservoir to raise or lower at will the mercury level in said reservoir. 110

4. In a tape-controlled printing telegraph system, in combination, a body of insulating material having a transverse mercury reservoir adapted to be closed by a tape passed over the same, an insulating body spaced from the first for passage of the tape and having a transverse row of contacts for engagement with mercury protruding through perforations in the tape, and a horizontal tubular mercury container communicating with the 120 mercury reservoir, pivoted to be rocked on its axis and having an angularly extending portion. 125

5. In a tape-controlled printing telegraph system, in combination, a body of insulating 130

material having a transverse mercury réservoir adapted to be closed and opened by a perforated tape passed over the same, a contact arranged to be engaged by mercury 5 emerging from the reservoir through a perforation in the tape, and means to prevent escape of mercury from the reservoir when the tape is to be removed.

6. In a tape-controlled printing telegraph 10 system, in combination, an insulating body having a transverse mercury reservoir adapted to be closed and opened by a perforated tape passed over the same, an insulating member arranged adjacent to the mercury réservoir to permit the passage of the tape and 15 having a contact in position to be engaged by mercury protruding through a perforation in the tape, means for holding the insulating member in position and permitting removal 20 of the same at will, and means for preventing escape of mercury from the reservoir when the insulating member is to be removed.

7. In a tape-controlled printing telegraph 25 system, in combination, an insulating body having a transverse mercury reservoir, an insulating body removably mounted adjacent to the said body to permit passage of a perforated tape between the two, a plurality of contacts mounted in said member to cooperate 30 with a body of mercury in said reservoir under the control of the tape, a plurality of terminals carried by said member and connected with said contacts, and a plurality of terminals 35 releasably engaging the first named terminals for connecting the same with a plurality of circuits.

8. In a tape-controlled printing telegraph 40 system, in combination, a fixed insulating body and a removable insulating body arranged to permit the passage of a perforated tape between the two, transverse contacts in 45 said bodies adapted to be selectively closed through perforations in such tape, fixed terminals arranged on the removable body and connected with the contacts in said body, and 50 spring terminals releasably engaging the fixed terminals for connecting the latter in a plurality of circuits and permitting removal of the removable body.

55 9. In a tape-controlled printing telegraph system, in combination, transverse upper and lower contacts spaced apart for passage of a perforated tape therebetween, a group of terminals connected with the upper contacts, a group of spring terminals, a support for the upper contacts and their terminals 60 removably positioned with the fixed terminals in releasable engagement with the spring terminals, and a support for the spring terminals.

65 10. In a tape-controlled printing telegraph system, in combination, a transverse row of insulated contacts having terminals, a removable support for said contacts and terminals, a longitudinal row of spring terminals re-

leasably engaging the first terminals, a support for the spring terminals, and contact means adjacent to said insulated contacts to permit passage of a perforated control tape.

11. In a tape-controlled printing telegraph 70 system, in combination, a body of insulating material having a contact exposed at the surface of said body, mechanism for passing a perforated tape over said contact, and a body of insulating material spaced from the first 75 to permit passage of the tape and having a mercury reservoir adapted to be closed by the tape and permit the mercury to extend through perforations in the tape into engagement with the contact, said body having also 80 a recess beyond the contact to receive mercury carried from the reservoir by the tape.

12. In a tape-controlled printing telegraph 85 system, in combination, a body of insulating material having a contact exposed at the surface of said body, mechanism for passing a perforated tape over said contact, and a body of insulating material spaced from the first 90 to permit passage of the tape and having a mercury reservoir adapted to be closed by the 95 tape and permit the mercury to extend through perforations in the tape into engagement with the contact, said body having also means for recovering mercury carried from the reservoir by the tape.

13. In a tape-controlled printing telegraph 100 system, in combination, a reservoir adapted to contain mercury for protrusion of mercury through perforations in a tape passed across the reservoir, and a receptacle beyond the reservoir and underlying the path of the tape, into which mercury carried from the reservoir by the tape perforations may drop.

14. In a tape-controlled printing telegraph 105 system, in combination, an insulating body having a mercury reservoir from which mercury may protrude into perforations in a tape passing across the reservoir, said body having also a mercury receiver under the tape 110 into which mercury may fall which has been carried away from the reservoir by the tape perforations.

15. In a printing telegraph system, in combination, transmitting mechanism adapted 115 to send current over a transmission line; a receiver controlled by current so sent; and means for controlling the current sending operation of the transmitting mechanism; said controlling means including a plurality of control circuits and a plurality of contacts 120 therefor arranged in groups, confined bodies of mercury associated with the respective groups of contacts and adapted to flow into engagement with the latter; mechanism for feeding an insulating perforated control tape 125 between said contacts and the associated bodies of mercury to prevent such engagement except through the perforations in the tape; and actuating means for said feeding mechanism, under the control of current sent over 130

the transmission line to maintain the feed of the tape in harmony with the operation of the receiver.

16. In a printing telegraph system, in combination, transmitting mechanism adapted to send current over a transmission line; a receiver controlled by current so sent; and means for controlling the current sending operation of the transmitting mechanism; 10 said controlling means including a plurality of control circuits and a plurality of contacts therefor, a confined body of mercury associated with said contacts and adapted to flow into engagement with the latter; mechanism 15 for feeding an insulating perforated control tape between said contacts and the associated body of mercury to permit such engagement only through perforations in the tape; and actuating means for said feeding mechanism, 20 under the control of current sent over the transmission line to maintain the feed of the tape in harmony with the operation of the receiver.

17. In a printing telegraph system, in combination, transmitting mechanism adapted to send current over a transmission line; and means for controlling the current sending operation of the transmitting mechanism; said controlling means including a plurality 30 of control circuits, and a plurality of contacts therefor, a confined body of mercury associated with the said contacts and adapted to flow into engagement with the latter; and mechanism for feeding an insulating perforated control tape between said contacts and the associated body of mercury to prevent such engagement except through perforations in the tape.

18. In a printing telegraph system, in combination, a transmitter having a sunflower, a wiper traversing the same, a commutator operating in harmony with the wiper to send current impulses over a line, and electromagnetic means for arresting the commutator 40 and wiper with the latter on a selected contact of the sunflower; a plurality of stationary contacts connected with the sunflower to control said arresting means; and a confined body of mercury under a head for causing it 45 to flow into engagement with the stationary contacts under the control of a perforated tape to complete a control circuit for said arresting means.

19. In a printing telegraph system, in combination, a transmitter having a sunflower, a wiper traversing the same, a commutator operating in harmony with the wiper to send current impulses over a line, and electromagnetic means for arresting the 55 commutator and wiper with the latter on a selected contact of the sunflower; a plurality of stationary contacts connected with the sunflower contacts to control said arresting means; an insulating body in which the stationary contacts are arranged side by side;

an insulating body having a chamber containing mercury and provided with a slot permitting the mercury to engage the stationary contacts to complete a control circuit for said arresting means; said insulating bodies permitting the passage between the same of a perforated tape to prevent engagement of the mercury with said stationary contacts except through perforations 75 therein.

20. In a printing telegraph system, means for closing and opening a plurality of control circuits, comprising in combination, a row of insulated contacts arranged side by side, an insulating body having a mercury 80 chamber below said contacts, said body being apertured to permit mercury to engage the contacts, said insulating body permitting passage of a perforated tape between the same and said contacts to permit the mercury to engage a contact only when a perforation is immediately below the contact.

21. In a printing telegraph system, means for closing and opening a plurality of control circuits, comprising in combination, a 90 body of insulating material, a row of contacts arranged side by side in said body, an insulating body below the first and having a mercury chamber, said body being apertured to permit mercury to rise in said slot 95 into engagement with the contacts, said insulating bodies permitting the passage of a perforated tape between them whereby to permit the mercury to engage a contact only when a perforation is immediately below the 100 contact.

22. In a printing telegraph system, transmission circuit controlling means, comprising in combination, a row of contacts arranged side by side and insulated from each other, an insulating body below said contacts and having a mercury chamber provided with a slot registering with said row of contacts to permit mercury to rise in said slot into engagement with the contacts, said 105 contacts and insulating body permitting the passage of a perforated tape between them whereby to permit the mercury to engage a contact only when a perforation is immediately below such contact, and means for 110 putting a hydrostatic head on the mercury to cause the same to rise in the slot.

23. In a printing telegraph system, transmission-circuit controlling means, comprising in combination, a row of contacts arranged side by side and insulated from each other, an insulating body below said contacts and having a mercury chamber provided with a slot registering with said row of contacts to permit mercury to rise in said 120 slot into engagement with the contacts, said contacts and insulating body permitting passage of a perforated tape between them whereby to permit the mercury to engage 125 a contact only when a perforation is imme- 130

diatey below such contact, and a head-producing and relieving standpipe pivotally connected with said mercury chamber.

24. In a printing telegraph system, contact mechanism comprising in combination, an insulating body; a horizontal row of contacts arranged side by side therein; an insulating body below the first having separated mercury chambers; one chamber having a slot registering with a group of said contacts to permit engagement thereof by mercury rising in the slot, the other chamber having a slot registering with another group of said contacts for like operation; said insulating bodies permitting the passage therebetween of an insulated circuit-controlling tape having successive transverse rows of perforations to permit engagement of each mercury body with one or another of the contacts immediately above the same according to the positions of the perforations in the tape; and mercury standpipes pivotally mounted on the second named insulating body and connected with the respective mercury chambers.

25. In a printing telegraph system, contact mechanism comprising an insulating body having a mercury chamber and provided with an opening in its upper surface communicating with said chamber, a contact above said opening and engageable by the mercury in said slot through perforations in an insulating control tape passed between the same and the contact, and a mercury standpipe pivotally mounted on the insulating body and connected with said chamber.

26. In a printing telegraph system, contact mechanism comprising in combination an insulating body, a row of contacts therein having their lower ends exposed; an insulating body having a mercury chamber and provided in its upper surface with a slot registering with said contacts and communicating with the mercury chamber to permit mercury in the slot to engage the exposed ends of said contacts; supporting means for said bodies for the passage of a perforated tape therebetween to control such engagement, and permitting separation of the bodies for insertion of the tape; and a mercury standpipe pivotally connected with the

mercury chamber adapted when in upright position to put a head on the mercury in the chamber and when in lower position to drain mercury out of the chamber.

27. In a printing telegraph system, in combination, a body of insulating material, a row of contacts arranged side by side in said body, an insulating body below the first and having a mercury chamber provided with a slot registering with said row of contacts to permit mercury to rise in said slot into engagement with the contacts, said insulating bodies permitting passage of a perforated tape between them whereby to permit the mercury to engage a contact only when a perforation is immediately below such contact, rotary means for feeding the tape, and electromagnetic means for actuating said feeding means.

28. In a printing telegraph system, in combination, a body of insulating material, a row of contacts arranged side by side in said body, an insulating body below the first and having a mercury chamber provided with a slot registering with said row of contacts to permit mercury to rise in said slot into engagement with the contacts, said insulating bodies permitting passage of a perforated tape between them whereby to permit the mercury to engage a contact only when a perforation is immediately below such contact, a rotary member having teeth for engaging the tape to advance the same, a ratchet connected with said member to rotate the same, a pawl associated with the ratchet to rotate the same step by step, and electromagnetic means for actuating the pawl.

29. A mercury contact mechanism including a plurality of contacts carried by an upper insulating plate, a mercury reservoir thereunder, and spaced therefrom to permit the passage of a perforated insulating tape therebetween and means for lowering the level of mercury in said reservoir when replacement of said tape or inspection of said contacts is desired.

In testimony whereof we hereto affix our signatures.

GEORGE S. HILTZ.
